[57] **CLAIM**

The ornamental design for a packaging container, substantially as shown and described.

DESCRIPTION

FIG. 1 is a front perspective view of a packaging container embodying my new design;

FIG. 2 is a front elevational view;

FIG. 3 is a rear elevational view;

FIG. 4 is a side view looking from the left of FIG. 2, the opposite side being substantially a mirror image thereof; and

FIG. 5 is a top plan view.

The dash lines in FIGS. 3 and 4 represent perforations.

FIG. 1

FIG. 5

FIG. 2

FIG. 3

FIG. 4
